Primary Examiner — Mark Goodwin(74) *Attorney, Agent, or Firm* — Dorsey & Whitney LLP(57) **CLAIM**

The ornamental design for a press wheel, as shown and described.

DESCRIPTION

FIG. 1 is a perspective view of a first embodiment of a press wheel showing my new design;

FIG. 2 is a front view of FIG. 1;

FIG. 3 is a back view of FIG. 1;

FIG. 4 is a top view of FIG. 1;

FIG. 5 is a bottom view of FIG. 1, with left and right view omitted as being the same as the top and bottom views;

FIG. 6 is a perspective view of a second embodiment of a press wheel showing my new design;

FIG. 7 is a front view of FIG. 6;

FIG. 8 is a back view of FIG. 6;

FIG. 9 is a top view of FIG. 6; and,

FIG. 10 is a bottom view of FIG. 6, with left and right view omitted as being the same as the top and bottom views.

The dashed lines in FIGS. 1-10 are provided for environmental illustrative purposes only, and form no part of the claimed design. The break lines in FIGS. 6-10 illustrate indeterminate length of the structure shown on the press wheel.
